UNITED STATES PATENT OFFICE.

THEOPHLESS J. KING, OF MINERAL WELLS, ASSIGNOR OF ONE-HALF TO
JAMES OWEN, OF PALO PINTO, TEXAS.

WASHING-MACHINE.

SPECIFICATION forming part of Letters Patent No. 549,797, dated November 12, 1895.

Application filed May 22, 1895. Serial No. 550,167. (No model.)

To all whom it may concern:

Be it known that I, THEOPHLESS J. KING, a citizen of the United States, residing at Mineral Wells, in the county of Palo Pinto and 5 State of Texas, have invented certain new and useful Improvements in Washing-Machines; and I do hereby declare the following to be a full, clear, and exact description of the invention, such as will enable others skilled in the 10 art to which it appertains to make and use the same.

My invention has relation to washing-machines; and it consists in the novel construction and arrangement of its parts. 15 In the accompanying drawings, Figure 1 is a perspective view of my machine. Fig. 2 is a longitudinal sectional view. Figs. 3, 4, and 20 5 are detail views, Fig. 3 being a sectional view of a portion of the drum, showing one edge of the door, end of the cross-piece that holds the slats of the door together, lock, the hinge, and the countersunk thumb-screw, Fig. 4 being a perspective view of the door, and Fig. 5 a perspective view of one of the 25 slats.

My invention is described as follows:

A is a water-tight tub divided into two compartments a a' , the two compartments being divided by a water-tight partition a^2 . In the 30 front compartment is pivoted a cylindrical drum B. The journal b of said drum is secured in suitable bearings b' on the upper edge of the tub. One end of the journal b terminates in a crank-handle b^2 , by means of 35 which the drum is rotated. Said drum consists of heads C, to which are secured slats c. These slats are close enough to keep the clothes or any part thereof from falling out, but wide enough apart to allow the water to 40 flow freely between them. Each one of these slats c is beveled from the under side upward, bringing the slats to feather-edges c' at their upper corners. Said drum is provided with an opening d. Said opening is provided with 45 a door d'. The said door consists of two or more slats fastened together by cross-pieces d² d³, secured to their under sides. The cross-piece d² is just the distance from the end of the slats as is the thickness of the drum-head. 50 The cross-piece d³ is just the distance from the other end of the slat as is twice the thick-

ness of the drum-head, so that in putting the door in place I slip the long ends under one of the hoops d⁴ until the shorter ends may be let down by the inner edge of the hoop, put 55 in place under the hoop, then slipped until the cross-piece d² comes against the inner face of the drum-head. In order to hold the door in place a stay e is hinged to the cross-piece d² by the hinge e', and when the door is in 60 place this stay is turned up. In so doing its free end is brought against the inner face of the other drum-head and is kept in place by a countersunk thumb-screw e². (See Fig. 3.) The front compartment of said tub A is provided 65 with a cover E, which is hinged to the upper edge of the partition a². Said cover is water-tight, and when let down no water can escape between it and the upper edge of the compartment a. Said tub A is secured on the 70 upper face of a fire-box F, each end of the fire-box extending beyond the ends of the tub. Said fire-box is provided at its front end with a fire-grate and door f and at its rear end with a smoke-stack f². The front compartment of 75 the tub A is provided with a faucet g, situated near the bottom of said tub for the purpose of withdrawing the water therefrom. The compartment a' of said tub is provided with a faucet g² for the purpose of withdrawing the 80 water therefrom.

The device is provided with legs h, or it may be seated on a suitable frame or brickwork.

The two compartments a a' are partly filled with water, the clothing is put in the drum, 85 and the opening d, closed by the door d', is made in the fire-box and the water heated, and the washing is done by rotating the drum, and the clothing being carried through the water thereby is soon cleansed. 90

The slats being brought to a feather-edge at their upper corners makes the drum much easier to rotate, the water giving less resistance as the slats cut into the water. The water, because of the inclines, is caused to shoot 95 up into the drum as it is rotated with a force that penetrates the clothing and drives the dirt out, whereas if the edges of the slats were square no such operation of the water would take place.

The clothes thus washed are taken out and put in the rear compartment a', where they 100

are allowed to remain in the hot water to soak and bleach.

Having described my invention, what I claim as new, and desire to secure by Letters

5 Patent, is—

In a washing machine, substantially as shown, the combination of the cylindrical drum B, consisting of the heads C, slats c, and openings d; door d', consisting of slats c, 10 and cross-pieces d², d³; stay e, hinged to the

lower edge of cross-piece d³; thumb-screw e², countersunk in head C, and adapted to hold stay e, in place, substantially as shown and described and for the purposes set forth.

In testimony whereof I affix my signature 15 in presence of two witnesses.

THEOPHLESS J. KING.
